UNITED STATES PATENT OFFICE.

BURT E. LLOYD, OF NEW YORK, N. Y.

TALKING DOLL.

1,229,102.

Specification of Letters Patent.

Patented June 5, 1917.

Application filed December 14, 1916. Serial No. 136,918.

To all whom it may concern:

Be it known that I, BURT E. LLOYD, a subject of the King of Great Britain, and a resident of the city of New York, borough of Manhattan, in the county and State of New York, have invented a new and Improved Talking Doll, of which the following is a full, clear, and exact description.

This invention relates to speaking dolls of the "ma-ma" type.

The invention has for its general objects to improve the construction and operation of a sound-producing device for toys of this character so as to be reliable and efficient in use, comparatively simple and inexpensive to manufacture, and so designed as to produce a better articulation.

A more specific object of the invention is the provision of means for articulating the sound issuing from the reed, such means including an aperture having a resilient lip and spaced stoppers or valves which are passed through the aperture and coöperate with the lip to cause the articulation of the sound for producing a word, such as "ma-ma."

Another object of the invention is the provision of a novel combination of a sound-producing device, and means operated thereby for actuating the arms of the doll so that simultaneously with the speaking of the word "ma-ma" the arms will assume an appealing position.

With such objects in view, and others which will appear as the description proceeds, the invention comprises various novel features of construction and arrangement of parts which will be set forth with particularity in the following description and claims appended hereto.

In the accompanying drawings, which illustrate certain embodiments of the invention and wherein similar characters of reference indicate corresponding parts in all the views,

Figure 1 is a front view of a doll embodying the sound producing device and arm-actuating means;

Fig. 2 is a side view thereof;

Fig. 3 is a vertical section showing the bellows of the sound producing device compressed and the arms elevated;

Fig. 4 is a rear view of the sound-producing device;

Figs. 5 and 6 are detail views showing a different position of the articulating means;

Fig. 7 is a side view of a doll with a portion broken away to show a modified form of a sound producing device;

Fig. 8 is an enlarged sectional view of such device; and

Fig. 9 is a sectional view on the line 9—9, Fig. 8.

Referring to the drawing, A designates a doll which has mounted on or in its body a sound-producing device B, which may be in the form of a bellows, as shown in Figs. 1 to 6 inclusive, or may be in the form of a box having a flexible diaphragm, as shown in Figs. 7 to 9 inclusive.

Referring to the construction shown in the first group of figures, the stationary plate 1 of the bellows has the usual reed 2 that communicates with a sound box 3 and with the chamber 4 of the bellows. The sound box 3 has an aperture 5 through which the sounds issue. The means for articulating the sound comprises an annular lip 6 extending around the aperture 5, and a plurality of disks or valves 7 which are passed through the lip as the bellows is compressed, whereby the sound from the reed will be articulated. The disks 7 are mounted on a stem 8 which is fastened to the movable plate 9 of the bellows. Normally the disks 7 are disposed within the sound box, as shown in Fig. 5, and when the bellows is compressed, the outermost disk first passes through the resilient lip 6 and cuts off the sound, and as soon as this disk passes beyond the lip, the sound again issues until it is cut off by the second disk or valve, making a two-syllable word. More disks can be used for making a sound of more than two syllables. If desired, the disks 7 may have resilient edges to pass through the aperture 5, in which case the resilient lip 6 is not required.

Simultaneously with the uttering of the word "ma-ma" the arms of the doll will be elevated to an appealing position. For this purpose the arms 10 are connected together by a wire frame or yoke 11 mounted to swing in bearing elements 12 on the doll. The center of the yoke has an arm 13 formed thereon, which is adapted to be engaged by a lever 14, the free end 15 of which has a wiping engagement under the arm 13. On

the fixed plate 1 of the bellows is a member 16 which passes through an opening 17 in the member 9 and engages the lever 14 so as to throw the same from dotted-line position, 5 Fig. 2, to the position shown in Fig. 3, when the bellows is compressed, whereby the arms 10 are elevated. When the pressure on the bellows is removed the arms return to normal position, as does also the lever 14. The 10 hinge 18 of the lever is shown as a piece of leather that returns the lever to normal position when the member 16 moves away from the lever by the expansion of the bellows.

In the form of the sound-producing device shown in Figs. 7 to 8, the device comprises a box 20 which has its open side closed by a flexible diaphragm 21. Connected with the diaphragm is a stem 22 on which are the valves or disks 23 that pass through the 15 aperture 24 of the sound box 25 to cause the articulation of the sounds. The stem is confined to a rectilinear reciprocatory motion by being guided in a bearing 26. The diaphragm is held outwardly by a helical spring 27 suitably arranged within the box. The diaphragm is shown in its normal position, Fig. 8, but when it is compressed air is forced out of the box through the reed, whereby the sound is produced, such sound 20 being interrupted by the disks 23 passing through the aperture in the sound box. The disks may have resilient edges 28 to take the place of the resilient lip 6 shown in Figs. 3 to 6 inclusive.

35 From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown 40 is merely illustrative and that such changes may be made when desired as fall within the scope of the appended claims.

Having thus described my invention, I claim as new and desire to secure by Letters 45 Patent:

1. A sound producing device comprising a sounding device, an air chamber having

an aperture, and valves movable through the aperture to successively close and open the same.

55

2. In a sound producing device, a sounding element, an air chamber having an aperture through which sounds issue, and means for opening and closing the aperture, said means comprising a stem movable through the aperture and having spaced disks to close and open the aperture.

3. In a sound producing device, a sounding element, an air chamber having an aperture through which sounds issue, and means for opening and closing the aperture, said means comprising a stem movable through the aperture and having spaced disks to close and open the aperture, said aperture having a resilient lip which snugly hugs the disks 70 in passing through the aperture.

4. A sound producing device comprising a sounding element, an air chamber having an apertured part, and a valve part, said parts being relatively movable, one part having resilient means for effecting a stoppage of sound and also one element including spaced sound stopping portions.

5. A doll including movable arms, a sound-producing device including relatively movable parts, a lever fulcrumed on one of the parts, a member for actuating the lever by the relative movement of the said parts, a member connected with the arms of the doll and with which the lever has a wiping engagement, whereby the arms move simultaneously with the operation of the sound-producing device.

6. A doll including movable arms, a frame connected with the arms and having a member, a sound-producing device including a relatively movable part, a lever mounted on the movable part of the sound-producing device and having a wiping action with the said member, and an element engaged with the fixed part of the sound-producing device and extending through the movable part for engaging with the lever, whereby the element, lever and member form a motion-multiplying means between the movable part 100 of the sound-producing device and the arms of the doll.

BURT E. LLOYD.
